CLAIM

The ornamental design for wooden closet wheel, as shown and described.

DESCRIPTION

FIG. 1 is a perspective view of a wooden closet wheel of the present invention, illustrating a mounting pole in phantom outline, the broken lines showing the mounting pole for illustrative purposes only and forming no part of the claimed design;

FIG. 2 is a top plan view of the invention;

FIG. 3 is a bottom plan view of the invention;

FIG. 4 is a front elevational view of the invention, illustrating the mounting pole in phantom outline, the broken lines showing the mounting pole for illustrative purposes only and forming no part of the claimed design, the rear elevational view of the invention being a mirror image thereof; and,

FIG. 5 is a left-side elevational view of the invention, illustrating the mounting pole in phantom outline, the broken lines showing the mounting pole for illustrative purposes only and forming no part of the claimed design, the right-side elevational view of the invention being a mirror image thereof.
